UNITED STATES PATENT OFFICE.

DENT L. LYDICK, OF QUAKER CITY, OHIO.

DESIGN FOR A PENHOLDER.

SPECIFICATION forming part of Design No. 22,264, dated March 7, 1893.

Application filed February 6, 1893. Serial No. 461,265. Term of patent 7 years.

To all whom it may concern:

Be it known that I, DENT L. LYDICK, a citizen of the United States, residing at Quaker City, in the county of Guernsey and State of Ohio, have invented and produced a new and original Design for Penholders and Paper Cutters, of which the following is a specification, reference being had to the accompanying drawings, showing a part thereof.

Figure 1 is a front side view of the pen holder and paper cutter, and Fig. 2 is a rear side view of the same illustrating my design.

The leading feature of my design is a pen holder and paper cutter whose lower stem portion is a tube, and on the front side is expanded, about midway the length of the holder, into the representation of a feather in relief, the tubular stem being continued as a tapered convex rib or corrugation through the curled filaments or brush forming the vane, without break or joint, while upon the rear side of the stem there is a longitudinal joint or seam throughout its whole length whose edges at the upper end diverge into and are continuous with the marginal or outer edges of the feather whose delineations upon this side are sunken or in intaglio.

A represents the tapered tubular stem which, upon the front side, is expanded about midway the length of the holder without joint or seam into the representation of a feather having a convex middle rib or corrugation B tapering continuously from the stem A to the

end. Extending laterally from the rib B are curled filaments a a a a in relief terminating in an irregular margin. Upon the opposite side the tapered stem A has a longitudinal joint or seam b whose edges lie closely adjacent throughout the stem portion, and, about the middle of the holder, diverge and run continuously into the marginal or outer edges of the feather. Upon this side of the feather, the representation of the stem through the feather is a concave tapering corrugation B' corresponding to the convex corrugation upon the other side, and the curled delineations of the filaments of the feather as shown at a' a' a' a' are depressed or sunken so as to show in intaglio, and they correspond to the raised delineations a a a a upon the opposite side. At the lower end of the stem A upon the rear side the edges are cut away and bent inwardly at c to form a socket for a pen point.

I am aware that an ostrich feather stuck into a metal ferrule has been patented as a new design, and I make no claim to any such design.

What I claim is—

The design for a pen holder and paper cutter substantially as herein shown and described.

DENT L. LYDICK.
